UNITED STATES PATENT OFFICE

121,122

DESIGN FOR A BRAKE ACTUATOR OR SIMILAR ARTICLE

Charles S. McCarthy, Toledo, Ohio, assignor to
The Legan Gear Company, Toledo, Ohio, a
corporation of Ohio

Application March 30, 1939, Serial No. 83,928

Term of patent 3½ years

To all whom it may concern:

Be it known that I, Charles S. McCarthy, a citizen of the United States, residing at Toledo, in the county of Lucas, State of Ohio, and United States of America, have invented a new, original, and ornamental Design for a Brake Actuator or Similar Article, of which the following is a specification, reference being had to the accompanying drawing, forming part thereof.

Figure 1 is an isometric view of a brake actuator showing my new design;

Figure 2 is a rear elevational view of the brake actuator of my design.

The dominant features of my design reside in the parts shown in full lines.

I claim:

The ornamental design for a brake actuator or similar article, as shown and described.

CHARLES S. McCARTHY.
